UNITED STATES PATENT OFFICE.

NATHAN PURDY, OF FALL BROOK, PENNSYLVANIA.

PIPE-TONGS.

SPECIFICATION forming part of Letters Patent No. 247,406, dated September 20, 1881.

Application filed July 15, 1881. (Model.)

To all whom it may concern:

Be it known that I, NATHAN PURDY, of Fall Brook, in the county of Tioga and State of Pennsylvania, have invented a new and Improved Pipe-Tongs, of which the following is a specification.

My invention consists in linking the jaws of the tongs together at their outer ends and linking one of the jaws permanently to the end 10 of the handle or lever, the other jaw being adapted to be connected to the lever so as to grasp upon the pipe by means of a loop or similar device hinged or pivoted upon the end of the lever, and adapted to be placed over the 15 end of said jaw, as hereinafter more fully described.

In the accompanying drawings, Figure 1 is a side view of my improved tongs. Fig. 2 is a view of the edge or back of the tongs, and 20 Fig. 3 is a cross-section on the line xx of Fig. 1.

Similar letters of reference indicate corresponding parts.

In the drawings, A represents the handle or lever; and B B' represent the jaws, which are 25 serrated upon their inner faces as shown. The jaw B is attached permanently to the end of the lever by means of eye a , formed on the end of the lever and the hook b formed on the end of the jaw, and one end of the jaw B' is permanently attached to the outer end of the jaw 30 B by means of the strong link d , which is of sufficient length to permit the jaw B' to be placed over and upon the pipe to be turned. The other end of this jaw is formed into the

hook h , so that when the jaw is placed over and 35 upon the pipe the swinging loop or link D, which is bolted to the lever by the bolt j , may be placed over the hook h , as shown in Fig. 1, and thus secure the tongs upon the pipe. When the tongs are thus attached to the pipe, 40 upon power being applied to the lever the jaws will automatically grasp upon the pipe by the action of the links, and thus relieve the operator of the necessity of gripping the tongs upon the pipe by hand-power, as with the tongs of 45 ordinary construction; and when the lever is brought to position for taking a new hold upon the pipe the jaws of their own weight will turn upon the pipe to the proper position, ready to again grasp the pipe firmly when power is again 50 applied to the lever.

These tongs are strong, durable, cheap of construction, and, as appears from the above description, easily and quickly operated, and they are not liable to get out of order.

Having thus fully described my invention, I claim as new and desire to secure by Letters Patent—

The combination, with the lever A, provided with the eye a and pivoted link D at its lower 60 end, of the jaws B B', having at their upper ends the hooks b and h , and connected together at their lower ends by link d , substantially as herein shown and described.

NATHAN PURDY.
